UNITED STATES PATENT OFFICE.

ELEANOR THEODORA LAROCQUE, OF BERNARDSVILLE, NEW JERSEY.

FURNITURE CABINET.

Application filed June 3, 1926. Serial No. 113,379.

My invention relates to improvements in furniture cabinets and has to do more particularly with a piece of furniture preferably for household use, but adaptable also 5 for office use, which may serve either as a typewriter enclosure and stand, or as a working stand and cabinet for sewing or other household work.

In the accompanying drawings Fig. 1 is 10 a front elevation of an apparatus in its closed condition illustrating my invention; Fig. 2 is a side elevation partly in section of the apparatus of Fig. 1 looking from right to left with the front portion in a closed position; Fig. 3 is a view similar to Fig. 2 15 with the front portion open and resting on its support; Fig. 4 is a sectional view in the line 4 of Fig. 3, looking downward, with the movable parts in open position; Fig. 5 is a 20 view similar to Fig. 3 with the front portion in half open position; Fig. 6 is a portion of the apparatus of Fig. 2 showing a modification.

Referring to the drawings, my apparatus 25 consists of a box-like enclosure or cabinet 1, having preferably four sides and supported on four legs, 2, which may extend either to the top of the cabinet (Fig. 1) or to the bottom thereof, as in Figs. 3, 5. The front section 3 of said box or cabinet is hung at the bottom by any suitable means to the body of 30 said box or cabinet, such as pins 4. A knob 5 on the front 3 enables it to be easily opened and closed. A drawer 6 may be inserted in 35 the frame and so arranged that when the front section 3 is opened outward and downward, it may be supported by 6 (Fig. 3). Attached to said front part 3 is leaf or wing portion 7 by hinges 8 and leaf or wing portion 9 by hinges 10. Said leaf or wing portions 40 may be of equal or of unequal size, or one or both may be omitted, as in Fig. 3. Normally, said wings are folded over and lie on top of or against part 3, as in Figs. 2, 45 5 and 6. They are open in Fig. 4. One or more drawers 11 may, if desired, be inserted in the upper part of the cabinet.

The drawer 6 may serve as a receptacle 50 for paper or other articles, and also as a support for the front 3 when the latter is opened, as in Fig. 3. It is desirable that 6 should be drawn into its supporting position before part 3 is opened; and to this end notches 6^a are cut in the sides of drawer 6, 55 and the lower side of 3 is left with square

edges, so that while 6 is closed (Fig. 2) the sides of drawer 6 are just flush therewith, and 3 cannot be opened until 6 is drawn out with the notches 6^a immediately below 3, as in Figs. 3 and 5. And, again, front 3 must 60 be closed while drawer 6 is in its open position, for it cannot be closed while drawer 6 is closed. This arrangement prevents liability of unusual strain on pins 4 on which 65 part 3 swings.

Fig. 6 shows a modification in which drawer 6 is replaced by two flat bars 06 each sliding in and out of the cabinet to serve as supports for part 3 when opened. Each bar 06 has a notch 6^a in such place that the bars 70 must be drawn into supporting position before part 3 can be opened, and the latter must be closed before the bars are moved back into the cabinet.

The apparatus may be used for several 75 purposes. It may be employed as a container and stand for a typewriter, the latter being entirely inclosed in the cabinet 1 when the front section 3 is closed, as in Fig. 1, and moved forward to rest on said section 3 when 80 the latter is opened into the position shown in Figs. 2 and 4; and in such use, one or both wings 7 and 9 may serve as convenient supports for writing paper and tools. Or it may serve as a writing desk, the box portion 85 enclosing writing paper and tools when section 3 is closed, and the latter serving as a writing table when opened as in Figs. 3, 4. Or it may serve as a sewer's cabinet, the materials, thread, needles, etc. being confined 90 when the front section 3 is closed; and when the latter is opened, it will make a convenient support for holding or cutting the cloth. Moreover, the apparatus when neatly made 95 of hard wood or other suitable material and with or without being decorated, becomes an attractive article of furniture either for the home or for office.

I claim:

1. An article of cabinet furniture having 100 a box-like enclosure supported on legs with sides and back and a movable front held at its lower edge on which it swings from vertical to horizontal position, and vice versa, supporting means movable into and out of 105 said apparatus, independently of the movement of said front, and on which the latter may rest when in horizontal position, and means associated therewith for preventing said front from being swung into horizontal 110

- position until after said supporting means have been moved into position to support the same.
2. An article of cabinet furniture having a box-like enclosure supported on legs, with sides and back and a movable front held at its lower edge on which it swings from vertical to horizontal position, and vice versa, supporting means for sustaining said front when in horizontal position, means associated therewith whereby said front may be held in vertical position until after said supporting means are in position to sustain the same, and a wing hung to a vertical edge of said front and adapted to open and enlarge the area thereof when in horizontal position.

3. An article of cabinet furniture having a box-like enclosure supported on four legs extending to the top thereof and forming corner supports for its sides, a front portion hung at its lower edge on which it swings from vertical to horizontal position, and vice versa, sliding means movable into and out of said article, independently of the movement of said front for supporting said front when in horizontal position, and means associated therewith whereby said front is held in vertical position until after said sliding means have been moved to support the same when in its horizontal position.
